UNITED STATES PATENT OFFICE.

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY.

BUTTONHOLE-SEWING MACHINE.

Application filed June 6, 1921. Serial No. 475,222.

To all whom it may concern:

Be it known that I, BERNARD T. LEVEQUE, a citizen of the United States, residing at Wenham, in the county of Essex and State 5 of Massachusetts, have invented certain new and useful Improvements in Buttonhole-Sewing Machines; and I do hereby declare the following to be a full, clear, and exact description of the invention, such as will 10 enable others skilled in the art to which it appertains to make and use the same.

The invention relates to sewing machines and more particularly to machines for sewing buttonholes in which the work is fed 15 during the sewing to space the stitches along the edge of the buttonhole.

In machines of this type the work is usually carried by a work clamp within which it is accurately positioned previous to each 20 buttonhole sewing operation and by which it should be held until the completion of a buttonhole, the sewing of which has once been started. If, however, the thread should break during the sewing, the reciprocation 25 of the needle or needles and the feed of the work may continue until the buttonhole sewing cycle is completed and the work released. Should this occur the work must be repositioned in the clamp with extreme care 30 in order that the operations on the work may be repeated at the exact points operated on in the previous cycle in which the break occurred. The operator therefore endeavors 35 to stop the machine upon the breaking of the thread before the cycle is completed. To relieve the operator of this duty and to insure the immediate interruption of the buttonhole making cycle upon the breaking of the thread the present invention contemplates 40 the provision of means which operates to stop the feed of the work upon the breaking of the thread. The progressive operation of the needles along the work is thus arrested so that they will operate idly until 45 the machine is stopped by the operator. The needle or needles may then be re-threaded and the sewing be resumed at the point where the break occurred, thus completing 50 the interrupted cycle and finish the buttonhole that had been started previous to the breaking of the thread.

A preferred form of the invention is shown in the accompanying drawing applied to the buttonhole sewing machine 55 shown and described in application No.

255,849, filed Sept. 26, 1918. In the drawings Fig. 1 is a side elevation showing the above machine with the preferred form of the invention applied thereto, and Fig. 2 is a vertical sectional view on line 2, Fig. 1. 60

The machine shown in the drawings is provided with a stitch-forming mechanism comprising an upper needle 2 and an under needle and looper (not shown) which cooperate in forming a well known type of over-seam buttonhole stitch. The buttonhole is cut progressively during the sewing by a small cutter carried by a vertically reciprocating cutter bar 4. The work is carried by a work clamp indicated generally at 6 70 and the work is automatically spaced between buttonhole making cycles by a spacing gripper indicated at 8. The work clamp is moved lengthwise of the buttonhole to feed the work by a feed cam secured to a cam shaft which also carries cams for controlling and operating various mechanisms of the machine.

The cam shaft is driven at a high speed 75 at the beginning of each cycle to effect the closing of the clamp and other preliminary operations, is given a step by step movement during the sewing to feed the work and space the stitches and is again driven at a high speed at the completion of the sewing 80 to return the work clamp to its initial position to operate a cutter for cutting the upper needle thread, to open the clamp and to operate the work spacing gripper. The mechanism for thus operating the cam shaft comprises a worm wheel 12 and a worm 14 which engages the worm wheel and is adapted to be rotated either continuously at 85 a high speed or intermittently from an actuator shaft 16. The worm is secured to a sleeve 18 which is mounted to turn on the shaft 16 and is provided at its end with a clutch member 20. The mechanism for driving the worm at a high speed comprises a sleeve 22 mounted to turn on the shaft 16 and provided at its inner end with a clutch member arranged to be engaged with and disengaged from the inner zone of the clutch member 20 by lengthwise movement of the sleeve 22 on the shaft. The outer end of the sleeve carries an actuating pulley 24 which is continuously driven. The sleeve 22 is moved to throw the high speed drive into and out of action by a lever 26, which is operated by a cam on the cam shaft. 90 100 105 110

The mechanism which operates the worm to intermittently advance the cam shaft during the sewing and thus feed the work comprises a clutch sleeve 28 adapted to engage the outer zone of the clutch member 20 and mounted to rotate and slide on the inner end of the sleeve 22. The clutch sleeve is oscillated during the sewing from the shaft 16 which also carries the cranks 30 and 32 for actuating the stitch-forming mechanism and carries a clutch 34 adapted to be engaged with a clutch member on the actuating pulley 24 by movement of the sleeve 22. The mechanism for oscillating the clutch sleeve 28 comprises a lever 36, the lower end of which is connected by a link 38 to the sleeve and the upper end of which is carried on the inner end of a rock shaft 40. The outer end of the rock shaft is provided with an arm 42 which is connected to the upper end of a lever 44 by a link 46. The lower end of the lever is slotted to embrace a three-cornered eccentric 48 formed on the hub of the clutch member 34 and thus connected to rotate with the actuating shaft 16. Through these connections oscillating movements are imparted to the clutch sleeve 28 whenever the shaft 16 is being driven by the pulley 24 to actuate the stitch-forming mechanism.

The clutch sleeve 28 is disengaged from the clutch member 20 at the end of its forward stroke and is re-engaged with the clutch member 20 at the end of its return stroke through an eccentric 50 driven from the shaft 16 through a worm 52 and worm wheel 54. The eccentric is engaged by the rear end of a link 56, the forward end of which slides through a block 58 pivoted to one arm of a lever 60. The block is held yieldingly in engagement with a shoulder on the link 56 by a spring 62. The other arm of the lever 60 is provided with arms embracing the clutch sleeve 28 and carrying pins projecting into an annular groove in the sleeve.

The mechanism for arresting or interrupting the feed of the work upon the breaking of the upper needle thread comprises a latch slide 64 mounted to slide vertically in a fixed guideway 66 and so arranged that its lower end may be brought into the path of a shoulder 68 on the rear arm of the lever 60 when the clutch sleeve 28 is in its disengaged position. The latch slide 64 is normally held out of the path of the shoulder 68 by a pivoted controlling finger 70, the forward end of which is provided with a thread eye for engaging the upper needle thread between the tension device 72 and the guide post 74. The rear end of the controller finger is connected by a cord 76 with the latch slide 64. During the normal operation of the machine the pivoted controller finger 70 is retained by the thread

in such position that the latch slide 64 is held up out of the path of the shoulder on the clutch operating lever 60. Should the thread break, however, the controller finger is then released and the latch slide drops 70 into position to engage the shoulder 68 on the lever 60 when the clutch sleeve 28 is disengaged from the clutch member 20 and prevents the re-engagement of the clutch sleeve and thus renders the feed mechanism 75 inactive and arrests the feed of the work at the point in the cycle where the break in the thread occurred. The controller finger may be provided with an adjustable counter-weight 78 for partially counter-balancing 80 the weight of the latch slide 64.

A similar mechanism may be utilized for arresting the feed of the work in case the under thread breaks and such a mechanism is shown. This mechanism comprises a 85 latch slide 80 arranged to engage a shoulder 82 on the lever 60 and normally supported in inactive position by a controller finger 84, the forward end of which is provided with a thread eye for engaging the under thread 90 between the tension device 86 and the guide 88 and the rear end of which is connected with the latch slide by a cord 90 through which the slide is normally supported in 95 inactive position.

While it is preferred to utilize the specific construction and arrangement of parts shown and described in embodying the invention in the machine of the patent above referred to it will be understood that this construction and arrangement is not essential and may be varied as found desirable or best suited to the construction and mode of operation of the machine in which the invention is to be embodied.

What is claimed is:

1. A sewing machine having, in combination, stitch forming mechanism, work feeding mechanism, and means for stopping the work feeding mechanism only, upon the breaking of the thread.

2. A sewing machine having, in combination, stitch forming mechanism, work feeding mechanism, an actuator, connections through which the stitch forming mechanism is operated from the actuator, connections through which the feed mechanism is operated from the actuator, and means for rendering the latter mechanisms inoperative upon breaking of the thread without stopping the stitch forming mechanism.

3. A sewing machine having, in combination, stitch forming mechanism, actuator mechanism therefor, work feeding mechanism, and mechanism for stopping the feed only, upon the breaking of the thread.

4. A sewing machine having, in combination, stitch forming mechanism, a work clamp, mechanism for moving the clamp to feed the work, and means for rendering the

feed mechanism only inactive upon the breaking of a thread.

5. A sewing machine having, in combination, stitch forming mechanism, a work clamp, a feed cam shaft, mechanism for actuating the shaft to feed the work, and means for rendering the actuating mechanism inactive to feed the work during the continued operation of the stitch forming mechanism upon the breaking of the thread.

6. A sewing machine having, in combination, stitch forming mechanism, a work clamp, a clamp feed mechanism including a clutch, mechanism for intermittently engaging the clutch during the sewing, and means for preventing the engagement of the clutch upon the breaking of the thread.

7. A sewing machine having, in combination, stitch forming mechanism, feed mechanism for relatively feeding the stitch forming mechanism and work during the sewing, an actuator connected to operate both mechanisms during the sewing, and thread controlled means for rendering the feed mechanism inactive without disconnecting the stitch forming mechanism from the actuator.

8. A sewing machine having, in combination, stitch forming mechanism, feed mechanism for relatively feeding the stitch forming mechanism and work during the sewing,

and means for stopping the feed mechanism only upon the breaking of the thread.

9. A sewing machine having, in combination, stitch forming mechanism, feed mechanism for relatively feeding the work and 35 stitch forming mechanism during the sewing, an actuating clutch, means for engaging and disengaging the clutch to start and stop the sewing, a feed clutch, mechanism for engaging and disengaging the feed clutch for 40 each stitch forming cycle, and means controlled by the thread for preventing the engagement of the feed clutch.

10. A sewing machine having, in combination, stitch forming mechanism, feed mechanism for relatively feeding the work and 45 stitch forming mechanism during the sewing, a sewing clutch, a feed clutch, and means for controlling the feed clutch from the thread.

11. A sewing machine having, in combination, stitch forming mechanism, a sewing shaft for actuating the stitch forming mechanism, feed mechanism for relatively feeding the work and stitch forming mechanism during the sewing, connections for operating the feed mechanism from the sewing shaft, and thread controlled means for rendering the connections active or inactive.

BERNARD T. LEVEQUE.
